ELECTRONIC CALCULATING MACHINE

Isao Kitai, Osaka, Japan, assignor to
Sharp Kabushiki Kaisha, Osaka, Japan

Filed Feb. 18, 1975, Ser. No. 550,719

Claims priority, application Japan Aug. 19, 1974

Term of patent 14 years

Int. Cl. D18—01

U.S. Cl. D26—5 C

FIG.—1

FIG.—2

FIG.—3

FIG.—4

FIG.—5

FIG.—6

FIG.—7

FIG. 1 is a front perspective view of an electronic calculating machine showing my new design;

FIG. 2 is a top plan view thereof;

FIG. 3 is a front elevational view thereof;

FIG. 4 is a right side elevational view thereof;

FIG. 5 is a sectional view thereof taken along the line 5-5 of FIG. 3;

FIG. 6 is a rear elevational view thereof; and

FIG. 7 is a bottom plan view thereof.

The broken line disclosure of the display numerals is for illustrative purposes only and forms no part of the claimed invention.

I claim:

The ornamental design for an electronic calculating machine, as shown and described.
